UNITED STATES PATENT OFFICE.

ROBERT C. RUSSELL, OF WILLIAMSPORT, PENNSYLVANIA, ASSIGNOR OF
ONE-HALF TO ANDREW W. SIEGEL, OF SAME PLACE.

SHEET-METAL PACKAGE.

SPECIFICATION forming part of Letters Patent No. 634,033, dated October 3, 1899.

Application filed March 1, 1899. Serial No. 707,250. (No model.)

To all whom it may concern:

Be it known that I, ROBERT C. RUSSELL, a citizen of the United States, residing at Williamsport, in the county of Lycoming and State of Pennsylvania, have invented a new and useful Sheet-Metal Package, of which the following is a specification.

This invention relates to cylindrical kegs or packages of sheet metal, its object being to so construct these devices that the head may be easily inserted into position in the cylinder or removed therefrom.

With this object in view the invention consists of the details of construction and combination of the several parts, as will be fully described hereinafter and particularly pointed out in the claims.

In the drawings, Figure 1 is a perspective view of a cylindrical package embodying my invention. Fig. 2 is a vertical section. Fig. 3 is a perspective view of the head detached. Fig. 4 is a section of the cylinder before the metal at the end is bent inwardly. Fig. 5 is a perspective view of a modified form of head. Fig. 6 is a section through the end of the cylinder and the modified form of head.

Similar reference-numerals indicate similar parts in the several figures.

1 represents the cylindrical body of the package, which, as shown, tapers slightly toward each end and is provided with a series of outwardly-projecting circumferential ribs or corrugations 2 to strengthen it and also to hold the ends of the package out of contact with the ground or floor when rolled over it.

The end 3 of the cylinder flares outwardly, and its edge is bent inwardly upon itself to form the flange 4. Immediately below the outwardly-flaring portion an inwardly-projecting corrugation or rib 5 is formed, which serves as a shoulder, upon which the head 6 rests.

The head is dished or concaved at its middle portion, as indicated at 7, and across the depressed portion a handle 8 extends, which is soldered or otherwise firmly secured to the head. The edge of the head is bent upwardly to form a flange 9, which flange flares outwardly to correspond with the outwardly-flaring end of the cylinder. The flange 9 is cut away, as indicated, to form two ends 10,

and the flange 4 is also cut away to form two openings 11, through which the ends 10 of the flange may pass, and as the head is turned the entire flange 9 will pass under the flange 4, and thereby lock the head in position.

In order to remove the head from the cylinder, the head must be turned until one of the ends 10 of its flange is between the openings 11, when if it is bent outwardly it will pass outside the opening 11, toward which it is turned, and the flange may in this manner be turned completely out of the flange 4. Instead of bending the end 10 outwardly the flange 4 may be bent inwardly at one of the openings 11, which will effect the same result.

In Figs. 5 and 6 I have illustrated a modified construction of the head, in which the metal of which the head is formed is crimped to form an upwardly-extending rib 12, extending centrally across it, and which serves the purpose of a handle and also permits expansion of the head. The head in this form need not be depressed at its central portion, and its flange 9 will preferably be at a right angle to it. The end of the cylinder will also be straight above the shoulder 5. Otherwise the construction and operation are the same as already described. The advantages of this last-described head are that it will turn easier in the cylinder and on account of its freedom to expand will fit more snugly into position.

By tapering the package slightly toward its ends and forming the circumferential ribs 85 the ends will be prevented from coming in contact with the ground or floor when rolled over it, and consequently the joint between the head and cylinder will not be liable to injury which otherwise might result. Both 90 ends of the cylinder may have removable heads, if desired; but if only one removable head is employed the joint between the other head and the end of the cylinder may be formed in a similar manner—that is, the head 95 will have an upwardly-extending flange formed around it and the cylinder will have the internally-projecting rib on which the head will rest, and the end of the cylinder will then be turned in over the flange of the 100 head and the joint closed by solder in the usual manner. The internally-projecting rib

will support the shoulder in position while the end of the cylinder is being turned in over the flange of the head. By this construction a head could be secured in the end of the cylinder after the cylinder was filled, as the rib will effectually support the head against any inward pressure caused by turning the end of the cylinder over it.

It will be understood that changes in the form, proportion, and minor details of construction may be resorted to without departing from the spirit or sacrificing any of the advantages of this invention.

Having thus described my invention, what I claim is—

1. The combination with the cylindrical body having its end bent inwardly upon itself to form a flange, and having an inwardly-projecting shoulder immediately below the flange, said flange having a portion cut away to form two openings, of a head adapted to be supported on the shoulder, and having an upwardly-projecting flange partly cut away to form two ends adapted to enter through

said openings, and a handle on the head, substantially as and for the purpose specified.

2. The combination with the cylindrical body having its end bent inwardly upon itself to form a flange, and an inwardly-projecting shoulder in the cylinder immediately below the flange, said flange being cut away to form two openings, of a head crimped to form an upwardly-projecting rib extending transversely across it, the edge of said head being bent upwardly to form a flange, and said flange being partly cut away to form two ends adapted to enter through the said openings, the crimp in the head forming a handle and also permitting expansion of the head, substantially as described.

In testimony that I claim the foregoing as my own I have hereto affixed my signature in the presence of two witnesses.

ROBERT C. RUSSELL.
